Inventor,
Norris C. Ingalls
by L. M. Harriman
Atty.

UNITED STATES PATENT OFFICE.

NORRIS C. INGALLS, OF NEWBURYPORT, MASSACHUSETTS.

HOISTING-HOOK.

1,341,427.

Specification of Letters Patent. Patented May 25, 1920.

Application filed January 2, 1920. Serial No. 348,768.

To all whom it may concern:

Be it known that I, NORRIS C. INGALLS, a citizen of the United States, and a resident of Newburyport, county of Essex, State of Massachusetts, have invented an Improvement in Hoisting-Hooks, of which the following is a specification.

This invention relates to a specific form of lifting hook which is especially designed and adapted for use in connection with a block and tackle, in lifting an automobile engine from its bed, the particular device illustrated being especially adapted to be engaged with a "Ford" engine, although it may be modified for use in connection with engines of other makes.

The object of my invention is to provide a form of lifting hook, which is of simple construction, so that it can be manufactured at small expense, which is strong and durable so that it cannot get out of order; which is adapted to be readily connected to, and disconnected from the engine and which, when connected, cannot become disconnected through accident.

I accomplish these objects by the means shown in the accompanying drawing, in which:

Figures 1, 2 and 3 are side elevations of a lifting hook embodying my invention and showing the manner of application to an engine cylinder.

Fig. 4 is an end view thereof, and

Fig. 5 is a detail view of the connecting pin which I employ.

As shown in the drawings, I provide a stiff iron bar, which is forged into loop-shaped form to provide a pair of depending arms *a* and *b*, which extend divergently from the suspension point and lie in the same plane. The arm *a* is provided with a toe *a'* at its lower end, which extends inward toward the other arm at approximately right angles thereto, and the arm *b* is provided with a hook *b'*, which is extended at right angles to the plane of the arms, and formed to provide a semi-circular recess, *b*², therein.

A locking pin *c* of rigid material, is also provided, said pin comprising a cylindrical portion *c'*, which is adapted to fit easily into one of the ports of the cylinder, and a portion *c*², of smaller diameter, forming a square shoulder *c*³. The diameter of the portion *c*² is slightly less than the diameter of the recess *b*² inclosed by the hook *b'*, so

that said portion *c*² may be passed into said hook *b'* and be held therein.

In practice the distance between the end of the toe *a'* and the side of the hook *b'* is slightly greater than the width of the top of the engine, so that it may be lowered thereon, as indicated in Fig. 1. When the toe *a'* is opposite the under side of the projecting ledge, (which is usually formed at one side of a "Ford" cylinder,) as in the full line position of Fig. 2, the device is moved edge-wise so that the toe engages beneath said ledge, as in the dotted line position of Fig. 2.

The manifold having been removed, the larger portion of the pin *c* is inserted in a cylinder port, as indicated in Fig. 3, and the smaller portion is engaged in the hook *b'*, as shown in Fig. 4, the arrangement being such that, when the arm *a* is engaged with the edge of the flange of the cylinder, the side of the hook *b'* will be engaged with the shoulder *c*³ of the pin, and, as the pin cannot be moved inward beyond the point indicated in Fig. 3, it will be apparent that the device, as a whole, will be locked against lateral movement.

As the pin *c* cannot be tilted to a material extent in the aperture in which it is inserted, when the device is pulled upward, it will form as rigid a connection between the arm *b* and the cylinder as does the toe *a'*, so that the engine cylinder may be lifted from its base thereby.

It will be obvious that the device may be disconnected from the cylinder as readily as it was attached thereto.

I claim:

1. A lifting hook for automobile cylinders comprising a pair of rigidly connected arms disposed approximately in the same plane and arranged to depend from their intermediate connecting portion, one of said arms having a toe at its end arranged to extend toward the other arm and the latter arm having a hook at its end disposed in a plane transverse to the plane of said arms and a rigid pin having one end portion thereof adapted to be inserted in an aperture in the cylinder and the opposite end portion to be held in said hook.

2. A lifting hook for automobile cylinders comprising a pair of rigidly connected arms disposed approximately in the same plane and arranged to depend from their intermediate connecting portion, one of said arms

105

110

having a toe at its end arranged to extend held in said hook, and being of smaller toward the other arm and the latter arm diameter than the portion first named, to having a hook at its end arranged to extend provide a shoulder to engage the inner side 10 transversely of said plane and a rigid pin of the hook.

5 having one end portion thereof adapted to be inserted in an aperture of the cylinder, the opposite end portion constructed to be

In testimony whereof I have signed my name to this specification.

NORRIS C. INGALLS.
